GRAVE VAULT

Thomas F. Kelley, Galion, Ohio; Veronica Kelley
executrix of Thomas F. Kelley, deceased

Application March 25, 1939, Serial No. 264,243

2 Claims. (Cl. 27—35)

This invention relates to improvements in burial vaults, and it has for its primary object to provide a device of this kind wherein the base is provided with rollers or other antifriction means which enable the pall bearers to place a casket thereon without the necessity of straddling the grave.

As a further and more specific object the invention aims to provide in a device of this kind, antifriction means on the casket base adjacent the mid and one end portion thereof and friction casket supports adjacent the other end—to the end that the antifriction means will facilitate sliding of the casket onto the base and will support the casket during such operation, and the friction means will act as a brake to cause the casket to cease lineal movement in respect to the base and come to rest at the proper point without requiring especial attention of the pall bearers.

The invention also resides in certain novel features of construction, combination and arrangement of the various parts, and in modes of operation—all of which will be apparent to those skilled in the art upon reference to the accompanying descriptive matter in connection with the accompanying drawing in which—

Figure 1 is a perspective view of a grave vault base embodying my invention—and shown resting upon the lowering straps of the lowering apparatus, ready to receive the casket;

Figure 2 is a lineal sectional view of said vault base and illustrating in dotted lines a casket being slid there onto;

Figure 3 is a view similar to Figure 2 but showing the casket and vault cover in place;

Figure 4 is a cross sectional view taken on the line 4—4 of Figure 3, and

Figure 5 is a cross sectional view taken on the line 5—5 of Figure 3.

Referring to the drawing by reference characters, numeral 6 designates the frame of the vault, or casket lowering apparatus. This frame has the usual upstanding bearings 7 for the ends of the gear controlled shafts 8, upon which are wound the vault-supporting and lowering straps 9. The bearings 7 at each end are connected by the cross bars 10 and the turning of the shafts 8 is controlled as usual by the hand cranks 11 indicated in Figure 1.

As shown in Figure 1 the vault base is disposed upon the lowering straps 9 ready to receive the casket 16 and vault cover 15 shown in Figure 3 and to be lowered into the grave. The vault base is designated by reference character 12 and has

the usual marginal flange 13 which supports the cover 15. The conventional latches 14 are provided to retain the cover in place.

To facilitate placement of the casket 16 on the base 12 without making it necessary for the pall bearers to straddle the grave, the base 12 is provided with transverse rollers 17 adjacent one end and at that side of the mid portion, as best indicated in Figure 1. These rollers are carried in bearings 18 which are suitably secured to the base 12.

Adjacent the other end of the base 12 there is provided the upstanding friction supports or pedestals, which in the present instance take the form of bulges 19 punched or indentations in the stock of the base 12. These serve the dual function of supporting the casket 16 when it is in position as shown in Figure 3 and acting as a brake to frictionally retard movement of the casket 16 lineally of the base over the rollers 17 when it reaches, or rather approaches its proper position shown in Figure 3. Since the innermost roller 17 is located short of the lineal midpoint of base 12, it is obvious that casket 16 will bear on pedestals 19 before it reaches the Fig. 3 position.

From the foregoing description taken in connection with the accompanying drawing, the operation of the device will doubtless be readily understood. The pall bearers simply slide the forward end of the casket onto the end roller 17 and push it into position as indicated in Figure 3. The two rollers support it and when the friction supports or pedestals 19 are reached they tend to frictionally brake or arrest lineal movement. It will be understood that the pedestals or supports 19 have their upper ends terminating in plane, or substantially so, with the upper peripheral portions of the rollers 17.

Having thus described the invention, what is claimed is:

1. In a casket receiving vault having a base and a removable casket-enclosing cover, raised anti-friction means fixedly disposed transversely of the upper surface of said base adjacent one end of the latter, said anti-friction means terminating short of the sides of said base so as not to interfere with said cover, raised, rounded-topped, casket-supporting friction means rising from said base adjacent each side thereof and having their upper rounded top ends substantially in plane with the top surface of said anti-friction means, and the lineal mid-point of said base lying between said friction and anti-friction means, whereby the anti-friction means provide

for quick starting of a casket onto said base and the rounded-topped, friction means cooperate with the anti-friction means after the fashion of a brake to enable the pall bearers to readily effect lineal centering of a casket on said base, said friction and anti-friction means being adapted thereafter to mutually support said casket in spaced parallel relation to said base.

2. In a casket receiving vault having a base and a removable casket-receiving cover, raised anti-friction means fixedly disposed transversely 10 of the upper surface of said base adjacent one end of the latter, a second raised, fixedly transversely disposed anti-friction means carried by said base between said first mentioned anti-friction means and the lineal mid-point of said base 15 and having its upper surface substantially in plane with that of said first-mentioned anti-

friction means, the ends of each of said anti-friction means terminating short of the sides of said base whereby to avoid interference with placement of said cover, and raised bevelled topped protuberance means adjacent each side of said base between its lineal mid-point and the other end thereof, the bevelled tops of said protuberance means lying substantially in plane with the top surfaces of said anti-friction means, whereby said anti-friction means provide for quick starting of a casket onto said base and the bevelled-topped protuberance means act as a brake to enable the pall bearers to readily effect lineal centering of a casket on said base, said anti-friction and protuberance means being adapted thereafter to mutually support said casket in spaced parallel relation to said base.

THOMAS F. KELLEY.
